Grodetzky & Polák and Felix Georg Lerk, both
of Prague, Czechoslovakia

Application July 7, 1933, Serial No. 679,437
In Germany October 24, 1932

11 Claims. (Cl. 30—3)

The invention relates to an appliance for cutting out the covers of conserve tins and makes use of the known supporting shield which is placed with its bent over U-shaped end on the 5 rim of the tin and in which the tractor wheel which rolls on the rim of the tin is journaled so as to be capable of being turned by means of a handle. The cutter has hitherto been fixed to this supporting shield or been mounted movably 10 thereon. In the former case for instance the lower edge of the short limb of the bent U-shaped end of the supporting shield is made in the form of a cutter edge or the cutter forms with the supporting shield in some other way a constructional unit and the tractor wheel is connected 15 to a lever mounted movably on the supporting shield; in the second case the arrangement must be such that the cutter is held in its operative position by special means, while the shaft of the 20 tractor wheel is journaled in a fixed bearing on the supporting shield. Consequently the plunging of the cutter into the cover, while the tractor wheel is at the same time pressed against the rim of the tin, requires at least a rocking or 25 some other movement of the cutter or tractor wheel out of its original position, in order to make it at all possible to place the supporting shield on the rim of the tin. Apart from this the construction of the appliance becomes so 30 complicated through the necessity of providing guiding means for the cutter or for the tractor wheel, that the appliance cannot be made in small dimensions.

The invention has for its object to obviate 35 these disadvantages. It consists substantially in this, that the supporting shield is not constructionally connected to the cutter and can thus be placed without difficulty on the rim of the tin and that the cutter is in the form of an edge- 40 on, wedge-shaped, tongue-like separate part which can be inserted with a sliding fit along the inside wall of the rim of the tin into the U-shaped end of the supporting shield. By this means the supporting shield is clamped in the 45 radial and vertical direction against the rim of the tin, the tractor wheel being at the same time pressed against the rim of the tin, so that, on the tractor wheel being turned, the supporting shield moves along the wedging surface on the 50 back of the cutter and stabs the latter into the cover. This relative motion between supporting shield and cutter can continue, until these two parts automatically become hooked one into the other and consequently the knife which has 55 been stabbed into the cover has to take part in

the motion of the tractor wheel rolling along the rim of the tin.

In the accompanying drawing a constructional example of the appliance is illustrated.

Fig. 1 shows a vertical section of the supporting shield with the tractor wheel placed loosely on the rim of the tin.

Fig. 2 a vertical section of the supporting shield clamped by the inserted cutter in the radial and vertical direction against the rim of the tin with the tractor wheel pressed against the rim of the 10 tin.

Fig. 3 shows a perspective view of the appliance corresponding to this action, seen from the cutter side.

Fig. 4 shows a similar perspective view with the supporting shield and the cutter which has already pierced the cover interhooked, and

Fig. 5 is a vertical section corresponding to Fig. 4.

The supporting shield 1, in which the shaft of the tractor wheel 2 is journaled, has the known U-shaped bent-over end or flange 3, which is adapted to be loosely placed on the rim of the tin (Fig. 1). The cutter is formed as a tongue 4, the thickness of which is made such that, on the cutter being inserted in the end 3 of the supporting shield (Fig. 3), the latter is clamped in the radial direction against the rim 5 of the tin, after the tractor wheel 2 bears against the lower edge of the rim of the tin (Fig. 2). The tongue 4 is provided at its lower edge with a projecting, blunt support 6, at a certain distance from which commences the inclined, upwardly ascending cutting edge 7 of the cutter. On the 35 tongue 4 being inserted into the end 3 of the supporting shield, the latter becomes clamped to the rim of the tin in the vertical direction, after the supporting shield has, owing to the support 6 bearing against the cover 8, been 40 somewhat raised and the tractor wheel 2 has thereby been pressed against the rim of the tin.

On the tractor wheel being thereupon turned by means of the handle 9, the supporting shield slides along the wedging surface on the upper 45 edge 10 of the tongue 4, so that the point 11 of the cutting edge of the cutter pierces the cover. This relative motion between the supporting shield and the cutter is completed as soon as the edge of the supporting shield becomes interhooked with the projection 12 of the tongue (Figs. 4 and 5). On the tractor wheel being turned further the cutter which has pierced the cover must therefore take part in the motion and cut out the cover.

What I claim is:

1. An appliance for cutting out the covers of tins, comprising a shield having a flange capable of extending over and around a rim of the tin, a tractor wheel supported in the shield for engagement under said rim, a handle for rotating the wheel, a cutter separate from said shield and adapted to be inserted under the flange and adjacent the inner face of the rim, and means operable by movement of said shield along the rim and relatively to the cutter to cause the cutter first to pierce the cover of the tin and then to become coupled to said shield to participate in its further movement on the rim to cut the cover out of the tin. 5
2. An appliance for cutting out the covers of tins, comprising a shield having a flange capable of extending over and around a rim of the tin, a tractor wheel supported in the shield for engagement under said rim, a handle for rotating the wheel, a cutter separate from said shield and adapted to be inserted under the flange and adjacent the inner face of the rim, an extension on said cutter adapted when the cutter is inserted 10 to clamp the rim of the tin both vertically and transversely between said shield and wheel while permitting relative movement between the shield and the cutter longitudinally of the latter, and means operable by such relative movement to cause the cutter first to pierce the cover of the tin and then to become coupled to said shield to participate in its further movement on the rim to cut the cover out of the tin. 15
3. An appliance for cutting out the covers of tins, comprising a shield having a flange capable of extending over and around a rim of the tin, a tractor wheel supported in the shield for engagement under said rim, a handle for rotating the wheel, a cutter separate from said shield and adapted to be inserted under the flange and adjacent the inner face of the rim, means operable by movement of said shield along the rim relatively to the cutter to cause the cutter first to pierce the cover of the tin and then to become coupled to said shield to participate in its further movement on the rim to cut the cover out of the tin. 20
4. An appliance for cutting out the covers of tins, comprising a shield having a flange capable of extending over and around a rim of the tin, a tractor supported on the shield for engaging under said rim, a handle for rotating the wheel, a cutter separate from said shield and adapted to be inserted under the flange and adjacent the inner face of the rim, means operable by movement of said shield along the rim and relatively to the cutter to cause the cutter to pierce the cover of the tin, and a blunt projection on the lower side of the means forming a fulcrum about which the cutter tilts when piercing the cover. 25
5. An appliance according to claim 4 in which the projection is integrally connected to the cutting edge by an intervening narrower portion of the cutter. 30
6. An appliance according to claim 2 in which the means operable by relative movement be- 35
7. In an appliance for cutting out the covers of tins, comprising a shield with a flange, a tractor wheel mounted therein, and an operating handle; a separate cutting member comprising an oblique cutting blade, a hook at one end of said blade adapted to engage the flange, an extension at the other end of the blade adapted for insertion under the flange and adjacent an inner rim face of the tin, a wedging surface on the upper edge of the member cooperating with the flange, and a fulcrum about which the cutting member can tilt during such cooperation. 40
8. In an appliance for cutting out the covers of tins, comprising a shield with a flange, a tractor wheel mounted therein, and an operating handle; a separate cutting member comprising an oblique cutting blade, a hook at one end of said blade adapted to engage the flange, an extension at the other end of the blade adapted for insertion under the flange and adjacent an inner rim face of the tin, and a wedging surface on the upper edge of the member cooperating with the flange. 45
9. An appliance for cutting out the covers of tins, comprising a shield having a flange capable of extending over and around a rim of the tin, a tractor wheel supported in the shield for engagement under said rim, a handle for rotating the wheel, and a cutter separate from said shield and adapted to be inserted under the flange and adjacent the inner face of the rim, said cutter having integral means operable by movement of said shield along the rim and relatively to the cutter to cause the cutter first to pierce the cover of the tin and then to become coupled to said shield to participate in its further movement on the rim to cut the cover out of the tin. 50
10. An appliance for cutting out the covers of tins, comprising a shield having a flange capable of extending over and around the rim of a tin, means on the shield to permit the shield to be manually operated on the tin, a cutter separate from said shield and having means to cooperate with the flange so that the cutter may be forced through the cover of the tin and then to cut the cover from the tin when the shield is forced to travel on the tin, and a hook on the cutter adapted to engage the flange when the cutter cuts the cover from the tin. 55
11. An appliance for cutting out the covers of tins, comprising a shield having a flange capable of extending over and around the rim of a tin, means on the shield to permit the shield to be manually operated on the tin, a cutter separate from said shield and having means to cooperate with the flange so that the cutter may be forced through the cover of the tin and then to cut the cover from the tin when the shield is forced to travel on the tin, and a hook on the cutter adapted to engage the flange when the cutter cuts the cover from the tin, said cutter with its means and the hook being composed of one integral member. 60
